UNITED STATES PATENT OFFICE.

GILBERT WRIGHT, OF WILKINSBURG, PENNSYLVANIA, ASSIGNOR TO THE WESTINGHOUSE ELECTRIC AND MANUFACTURING COMPANY, OF PENNSYLVANIA.

CIRCUIT-BREAKER.

SPECIFICATION forming part of Letters Patent No. 633,773, dated September 26, 1899.

Application filed March 23, 1899. Serial No. 710,230. (No model.)

To all whom it may concern:

Be it known that I, GILBERT WRIGHT, a citizen of the United States, residing at Wilkinsburg, in the county of Allegheny and State of Pennsylvania, have invented a new and useful Improvement in Circuit-Breakers, (Case No. 817,) of which the following is a specification.

My invention relates to that class of devices employed for automatically opening electric circuits when the current therein exceeds a predetermined amount, which are generally known as "circuit-breakers."

The object of my invention is to provide a circuit-breaker which shall be simple in construction and effective in operation and which may be more easily and certainly locked in operative position and released from such position when the conditions of the circuit demand it than has been possible in devices of this character heretofore employed.

In the accompanying drawings, Figure 1 is a side elevation of one form of circuit-breaker constructed in accordance with my invention, and Fig. 2 is a front elevation of the same, the circuit-breaker being in closed position in both figures. Figs. 3, 3^a, and 3^b are perspective views of certain details of the locking and releasing mechanism, and Fig. 4 is a detail view of one of the stationary contact-terminals and adjacent parts. Fig. 5 is a bottom plan view of another form of circuit-breaker, the cover being removed and parts being broken away. Fig. 6 is a transverse sectional view of the device shown in Fig. 5.

Referring now particularly to Figs. 1 to 4 of the drawings, 1 is a non-conducting base-plate or support which will ordinarily be a switchboard-panel of slate, marble, or similar material. The stationary contact-terminals 2 and 3 are mounted upon the face of the base-plate 1, and each is provided with a stud 4, which projects through the base-plate in order to connect with a bus-bar (not shown) at the rear of the switchboard. In the form here shown the two main contact-terminals 2 and 3 are in vertical alinement, and the upper one of these terminals has an upwardly-extending arm 5, having a socket or holder 6, in which is mounted a block 7, of carbon or

other substantially infusible conducting material. The lower main contact-terminal 3 is partially surrounded by a body of iron 8, there being an air-gap 8^a of any desired width at its upper end in order that the magnetic flux may be diverted at this point through the armature 9, which is mounted upon two arms 10, these arms being pivotally mounted in brackets 11, which may be parts of a single casting, the base of which may be suitably fastened to the panel 1 by means of bolts extending through the part 8. If the circuit-breaker is to be used in connection with alternating-current circuits, the parts 8 and 9 should be laminated; but for direct-current circuits they may form integral parts, respectively, of the brackets 11 and the arms 10, if found more convenient or desirable.

The arms 10 are provided with upwardly-projecting lugs or ears 10^a, having openings 7^c for a pivot-pin 10^b, beyond which they are joined by a transverse bar 12. A single arm 12^a projects from the middle of bar 12 and is provided with a scale 13, a weight 14, and with a screw 15 and thumb-nut 16 for adjusting the weight longitudinally on the arm 12^a.

The main movable contact member of the circuit-breaker comprises a bundle of curved laminæ 17, which are bolted or riveted to a supporting-arm or pair of arms 18, the ends 8^b of the laminæ 17 being free to be deflected as they are pressed against the faces of the stationary terminals 2 and 3.

For the purpose of making final contact with the upper terminal 2 I provide a small 85 plate or block 19^a and mount a small contact-block 19 upon the upper end of a spring-plate 20, this plate being securely fastened electrically and mechanically to the laminated contact 17. The plate 20 is extended downward below the lower end of the contact member 17 and is of such length and of such form as to make contact at all times with the face of the lower contact-terminal 3. The supporting-arms 18 for the contact 17 are pivotally mounted at their lower ends upon a rod 18^a, which is supported by the brackets 11 near the base, as shown.

A movable contact-block 21, of carbon or other substantially infusible material, corre- 100

sponding to the stationary block 7, is mounted in a socket 22 on the upper ends of a pair of arms 23, which arms are pivotally connected to the upper ends of the arms 18 by a pin 23^b.
 5 The arms 23 are provided with extensions 23^a, which project downwardly and inwardly beyond their pivotal support and are connected with the supporting-brackets 11 or other stationary portions of the devices by means of 10 coiled springs 24. The operating or closing handle 25 of the circuit-breaker is mounted upon a lever-arm 26, which comprises a sleeve 26^a and two arms 26^b, projecting therefrom inwardly. The sleeve 26^a is located between 15 the outer ends of brackets 11, and it is pivotally mounted upon the pin 10^b. A toggle-lever arm 27 extends between the pivot-pin 23^b and a pin 27^a, located in the free ends of lever-arms 26^b. The parts are so adjusted that 20 when the circuit-breaker is closed the joint between the arms 26^b and 27 of the toggle-lever is slightly beyond the dead-center—i. e., above the line joining the centers of the two pivot-pins 10^b and 23^b. The closing-lever 26 is provided on its under side with a lug 28, 25 that projects toward and within a short distance of the arm 12^a, so that when the current through the circuit-breaker increases to such an extent as to set up a magnetic flux 30 that pulls upon the armature 9 sufficiently to overcome the pull of weight 14 the arm 12^a will strike against the lug 28, and thus throw the toggle-joint downward below the line connecting the centers of the two pivot-pins 10^b and 23^b. The springs 24, acting in 35 conjunction with gravity, will throw the movable members of the circuit-breaker outward and downward and away from the stationary contact members. It will be seen 40 that the springs 24, the upper ends of which are attached to the projecting ends 23^a of arms 20, will first hold the shunt contact-terminals 21 and 7 in engagement until the contact member 17 has been separated from the 45 stationary terminals 2 and 3, and any current that is not shunted through the contact members 7 and 21 will be broken between the contact-pieces 19 and 19^a, since the former is supported upon a spring 20, that serves to hold 50 it in engagement with the piece 19^a after the contact member 17 has moved away from the co-operating terminal blocks 2 and 3. In order that this circuit-breaker may be easily closed and that it may respond quickly and 55 easily to the action of the tripping mechanism, I provide knife-edge bearings for the toggle-lever arms 26^b and 27. The portions of pivot-pin 23^b which are located in arms 18 and 23 are cylindrical and are loosely fitted 60 into the said parts. The middle portion of this pivot-pin is partially cut away to form a knife-edge portion 23^c, and this knife-edge rests in an angular cut-away portion of a bushing 23^d, the angle between the sides of which 65 is greater than that between the sides of the co-operating knife-edge portion, (see Fig. 3,) so that the two parts may turn with refer-

ence to each other without friction until the toggle-joint has passed its dead-center, when there is no longer any danger of binding between the parts on account of pressure exerted. 70

The portions of pivot-pin 27^a which are located in the ends of lever-arms 26^b are cylindrical, and the middle portion, which is located in the end of lever-arm 27, is partially cut away to form a knife-edge portion 27^b. This knife-edge portion is located in an angular recess in a bushing 27^c, the angle between the sides of the recess being greater 80 than that between the sides of the knife-edge portion 27^b for the same reason as that stated with reference to the bearing 23^d. (See Fig. 3^a.)

The portions of pivot-pin 10^b which are located in the ears 10^a and in the sleeve 26^a are cylindrical in form, and the portions which are located in the brackets 11 are partially cut away to form knife-edge portions 10^c. I provide bushings 10^d for the cut-away portions of the pivot-pin 10^b, each of which is cut away to form an angular recess, the angle between the sides of which is greater than that between the inclined sides of the portions 10^c for the reason stated with reference to bearings 23^b and 27^a. (See Fig. 3^b.)

Referring now to Figs. 5 and 6, the form of circuit-breaker here shown is designed and intended especially for use on railway-vehicles, and the operative parts are therefore 100 inclosed in a casing 1^a instead of being mounted upon a switchboard. The stationary terminal 29, to which main conductor 30 is connected, constitutes one terminal of the actuating-coil 31 of the circuit-breaker. The other terminal 29^a of the coil 31 is electrically connected to the movable member or blade 32 of the circuit-breaker, the latter being pivotally mounted upon the said terminal 29^a. A spring 33, here shown as coiled around the pivot-bearing 34 of the blade 32, but which may be of any desired construction, is provided for throwing the movable member or blade 32 outward when it is released. The other main conductor 35 is connected to a terminal block 36, in which is mounted a laminated contact member 37, having a beveled free end and located in a position to be engaged by the edge of the blade 32 or with a suitable block or plate 32^a, set in the edge of said blade. 110 The terminal block 36 is also provided with two plates 38, which are either of resilient material and somewhat flexible, so as to spring to permit the end of the blade to enter between them, or loosely mounted and pressed toward each other by means of springs of suitable construction, these devices being employed in order to shunt the current around the contact 37 and take any arcs which may be formed by the opening of the circuit-breaker. 115

The means for closing and locking the circuit-breaker are substantially like those described with reference to the preceding figures of the drawings. An operating-handle

is mounted upon a pivot 40 and is joined to the movable member 32 of the circuit-breaker by a toggle-lever 41, one arm 42 of which is rigid with the handle and the other arm 43 of which

5 comprises two plates or bars spaced apart in order to receive at one end the free end of arm 42 and at the other end blade 32, the connecting means for the respective ends being pivot-pins 44 and 45. The several pivot-pins 10 40, 44, and 45 are provided with knife-edge portions which coöperate with angular recesses of greater width in the bearings in the manner already described in order that the toggle-levers may respond readily and quickly 15 to any pressure exerted in the proper direction to move the toggle-joint over beyond the dead-center in the direction necessary to release the circuit-breaker.

In order to release the circuit-breaker when 20 the current exceeds the limit of safety, I provide a core 46 for the coil 31, (shown clearly in Fig. 6,) the end of which is located near to an armature 47 in the form of a lever, which is pivoted between its ends to a bracket 48 on 25 the casing, projects through an opening 48^a in a partition-plate 48^b, and is connected at its inner end to a rod 49, the latter being pressed outward by means of a coiled spring 50. The rod 49 is screw-threaded, and adjusting and locking nuts 51 are provided in 30 order to set the armature for any maximum current that may be desired. The outer end of the armature-lever 47 is pivoted to one end of an arm or rod 52, the other end of said arm 35 having a pin 53, so located when the circuit-breaker is closed that movement of the armature 47 by reason of excessive current through the coil 31 will cause the pin to engage the toggle-levers and move them a sufficient distance to carry the joint beyond the dead-center, when the spring 33 will complete the movement of the blade 32 to the position shown in 40 broken lines in Fig. 5.

It will be readily understood that the knife-edge bearings may be varied in number, as 45 well as in structure and arrangement, from what has been shown and described and that the details of construction may be otherwise modified without departing from the spirit 50 and scope of my invention.

I claim as my invention—

1. In an automatic electric circuit-breaker, the combination with the stationary and mov-

able contact-terminals, of toggle-levers for closing the breaker and constituting the sole 55 means for locking the same, and knife-edge bearings for said levers.

2. In an automatic electric circuit-breaker, the combination with stationary and movable contact-terminals, toggle-levers for closing the 60 breaker and constituting the sole means for locking the same, knife-edge bearings for said toggle-levers and electromagnetically-actuated means for moving the levers out of locking position. 65

3. In an automatic electric circuit-breaker, the combination with stationary and movable contact-terminals, of toggle-levers for supporting and actuating said movable terminals and knife-edge bearings for said levers, the 70 toggle-levers being so arranged and adjusted that the toggle-joint is movable beyond the dead-center to lock the circuit-breaker in operative position.

4. The combination with two relatively 75 movable devices or parts, of a joint therefor comprising a cylindrical pivot or bearing pin having one or more knife-edge portions, one or more angular recesses in one of said devices or parts occupied by said knife-edge portion 80 or portions, and one or more cylindrical bearings in the other device or part occupied by the cylindrical portion or portions of the pivot or bearing pin.

5. An antifriction pivot bearing or joint 85 comprising a part having a cylindrical recess and a part having an angular recess formed by two plane sides and a curved side, and a pivot-pin having a cylindrical portion which occupies said cylindrical recess and a knife- 90 edge portion which occupies said angular recess and has a curved side of less width than that of the recess.

6. The combination with two relatively 95 movable devices or parts, of a pivot-pin joining said parts and having one or more knife-edge portions and a bushing having one or more angular recesses occupied but not filled by said knife-edge portion or portions.

In testimony whereof I have hereunto subscribed my name this 20th day of March, 1899.

GILBERT WRIGHT.
